Application October 29, 1935, Serial No. 47,253

9 Claims. (Cl. 155—157)

The present invention relates to an improvement in posture chairs, particularly of the type in which the chair back is tiltably supported and is adapted to be adjusted as to angularity, height and tension, for the purpose of adapting the back to the particular person using the chair.

An object of the invention is to provide a tilting structure upon which the chair back is supported and which is adapted to be tilted against spring pressure, the arrangement of the tilting axis with respect to the spring and spring connection with the tilting structure being such that substantial support is provided for the back in the upright position, while, as the chair back is tilted rearwardly, the effort required to tilt the same through a given number of degrees is gradually diminished even though the spring pressure is gradually built up, this effort being represented during the initial tilting by rearward pressure exerted by the occupant of the chair and, as the chair back is increasingly tilted, by the rearwardly moving unbalanced weight of the person seated in the chair, so that throughout all but the initial range of tilt there is an approximate balancing of the weight of the occupant of the chair. In tilting back structures heretofore in use there was no compensation for this building up of spring pressure, with the result that, as the chair back was tilted towards its tilting limit, increasingly greater effort was required to maintain it in tilted position as the angle of tilt approached the limit position, while the initial tilting from the upright position required relatively less effort, and with the result that either very little support was provided for the back in the upright position if relatively easy tilting was permitted, or if adequate support was provided in the upright position relatively great effort was required to maintain the back in tilted position.

A further object is to provide a structure in which a relatively short spring may be advantageously used, and which lends itself to compactness, light weight and cheapness.

Another object is to provide improved adjustment means for adjusting the angle of the chair back with respect to the tilting member, whereby the person seated in the chair may conveniently adjust the handle with very little effort, and also to provide the handle for operating the angular adjustment means at a convenient location near the edge of the chair seat and at a point forwardly of the chair structure so that its operation will not necessitate a rearward shifting of the person's weight against the chair

back. Consequently the adjustment may be made while the back is not under tension. To this end it is particularly proposed to provide a universal joint connection between the handle and the adjustment means, whereby the adjustment axis is arranged longitudinally of the tilting element while the axis of the handle may extend at any desired angle thereto, and particularly forwardly and at one side of the swivel post.

A further object is to provide height adjustment means which enables the chair back to be conveniently raised or lowered, and which may be secured in adjusted relation without any possibility of the same becoming accidentally displaced and at the same time without exerting undue strain upon the parts, and further which permits the adjustment and securing while the user of the chair is seated therein in an upright and natural position. It is also proposed to provide such adjustment means whereby a very secure connection may be produced between the adjustable parts with very little effort on the part of the person making the adjustment. Another object is to provide a back member which may be readily removed for shipping purposes, without disassembly of any parts.

With the above and other objects in view embodiments of the invention are shown in the accompanying drawings, and these embodiments will be hereinafter more fully described with reference thereto, and the invention will be finally pointed out in the claims.

In the drawings:

Fig. 1 is a side elevation of a chair back tilting mechanism, according to the invention, the chair base and the upper portion of the chair back being broken away.

Fig. 2 is a longitudinal vertical sectional view.

Fig. 3 is a plan view, the seat being removed, and portions of the spider arms being broken away.

Fig. 4 is a side elevation of a chair back tilting mechanism, according to a modified form of the invention, a portion of one of the spider arms being broken away.

Fig. 5 is a plan view, partially broken away.

Fig. 6 is a force diagram, according to the invention.

Fig. 7 is another force diagram, according to the invention.

Fig. 8 is a force diagram, according to previously known practice.

Fig. 9 is a perspective view of the tilting mem-

ber employed in the embodiment illustrated in Figs. 1 to 3.

Fig. 10 is a perspective view of the universal joint means employed.

5 Similar reference characters indicate corresponding parts throughout the several figures of the drawings.

Referring to the drawings, and particularly to Figs. 1 to 3, thereof, the chair seat 10 has secured to its under side a pair of angle-iron spider arms 11-11, between which there is disposed a bearing member 12, the side portions 13-13 of which are secured to the respective sides of the spider arms by means of rivets 14. The bearing member 12 is provided with a cylindrical socket 15 in which is engaged the usual post 16 mounted upon the chair base, and upon which the chair seat is thus mounted for swivelling movement.

A tilting bracket member 17 is mounted upon 20 the spider arms rearwardly of the bearing member 12 by means of a bolt 18 extending through holes 19-19 provided in the sides of the spider arms and through apertured bearing portions 20-20 formed upon the sides of the bracket member 17, this bolt being provided at one end with a head 21, its other end being screw-threaded and engaged by a nut 22. The tilting member 17 is adapted to have limited tilting movement, and for this purpose stops 23-23 are formed upon 30 the outer sides of the bracket member 17 which in the normal non-tilted position abut vertical edge portions 24-24, especially formed upon the sides of the spider arms for this purpose. Stops 25-25 are also formed upon the outer sides of 35 the bracket member 17, their stop surfaces being inclined forwardly and downwardly and adapted in the limit position of rearward tilt to abut the lower edges of the sides of the angle irons.

A lateral base portion 26 is integrally formed 40 with and extends between the sides of the bracket member 17 and is provided at its rearward end with a downwardly extending flange 27. At the upper side of the base 26 there is provided an upwardly extending wall 28, also integrally formed with and extending between the sides of 45 the bracket member 17, the upper end of this wall being provided with a slot 29 at each side of which there are formed rearwardly projecting knife-edge bearing portions 30-30.

The knife edge bearing portions 30-30 engage 50 V-shape grooves 31-31 in the head 32 at one end of the spring bolt 33, the side surfaces of the bolt being preferably flat adjacent the head, as at 33^a, where the bolt is engaged in the slot 29, so that any tendency for the bolt to turn under 55 adjustment of the spring tension is prevented through engagement of said flat surfaces with the sides of the slot. The bolt extends forwardly in a downwardly inclined direction through an opening 34 provided in a vertically disposed bearing wall portion 35 of the bearing member 12, this portion being integrally formed with and extending between the side portions 13-13 of the bearing member. At the forward side of the bearing wall 35 there is formed an annular groove 36 in which is seated one end of the spring 37, the other end of the spring being engaged by a washer 38 having an abutment portion 39 which engages the extremity of the spring and forms 65 a seat thereof. The forward end of the bolt 33 is threaded and projects loosely through the washer 38 where it is engaged by an integrally threaded hand wheel or nut 40, which upon being turned moves the washer 38 toward or away from the wall 35 and adjusts the tension of the spring.

It will be observed that the point of engagement of the knife-edge bearing portions 30-30 with the spring bolt in the normal non-tilted position is substantially to the rear of the perpendicular distance line from the tilting axis of 5 the bracket member to the line of action of the spring force, and that the line of action of the spring force intersects the curve through which the spring connection with the bracket member moves. This is clearly shown in the diagram, 10 Fig. 6, in which A represents the tilting axis, B the point of the spring connection with the bracket member, C the curve through which the point B moves, P the line of action of the spring force, and T the torque arm represented by the 15 perpendicular distance between the tilting axis A and the line of spring action P.

By this arrangement the rate of increase of the tension applied to the spring as the tilting member is tilted rearwardly is gradually decreased 20 relatively to equal successive increments of the rearward angular movement, the points B¹, B² and B³ representing such equal increments of movement and the lines P¹, P² and P³ representing the changes in the line of action of the spring. 25 It will be seen that as the tilting member approaches its limit of tilt the additional tension imparted to the spring for a given angular movement is less than the tension applied during the same angular movement at the beginning of the 30 tilting action, and that the total distance the spring is compressed, represented by the distance B-B³ along the line P³, is substantially less than the total angular movement of the bracket member, represented by the distance B-B³ along the 35 line C. At the same time the torque arm T acting about the axis of tilt A is gradually decreased, as represented by the lines T¹, T² and T³. As the moment of force is the product of P and T, it will be seen that the successive increases in the 40 spring resistance gradually decrease as the tilting member is tilted rearwardly through equal successive increments of movement, in other words the increase, represented by the difference between the product of P¹ and T¹ and the product 45 of P and T, is greater than the increase represented by the difference between the product of P³ and T³ and the product of P² and T².

In Fig. 7 there is shown a force diagram similar 50 to that shown in Fig. 6, but on a reduced scale, and showing in addition the reaction of the person's unbalanced weight against the chair back supported by the tilting member, W representing the effort resulting from rearward pressure and unbalanced weight of the person and V representing the perpendicular distance between the tilting axis A and the line of the pressure W. The product of W and V will equal the product of P and T, and at the rearward limit of tilt the product of 55 W¹ and V¹ will equal the product of P³ and T³. 60

To consider the action in exemplary figures it will be assumed that the initial spring resistance represented by P is 250 pounds, that the radius distance A-B is 2 inches, and the distance A-W represented by the line V is 15 inches. The spring 65 is designed to have an increase in resistance of 1000 pounds per inch of compression. The limit of tilt of the point B along the curve C represented by the distance B-B³ is $\frac{1}{2}$ inch. The compression distance of the spring shown by the 70 longitudinal movement of the line of spring action from P to P³ is $\frac{1}{2}$ of an inch, so that if P is 250 pounds the increase of P³ over P is 343 $\frac{3}{4}$ pounds giving a total pressure of 593 $\frac{3}{4}$ pounds. The torque arm T is 1 $\frac{1}{2}$ inches and the torque 75

arm T^3 is $1\frac{1}{4}$ inches. The formula $P \times T = W \times V$ when reduced to figures will be

$$P(250) \times T(1\frac{1}{2}) = 375 = W(25) \times V(15)$$

5 This means that in the upright or non-tilted position the occupant of the chair will be supported by the tilting arm under 25 pounds pressure. In the fully tilted position the formula $P^3 \times T^3 = W^1 \times V^1$ when reduced to figures will be

$$10 P^3(593\frac{3}{4}) \times T^3(1\frac{1}{4}) = 742\frac{3}{16} = W^1(49) \times V^1(15)$$

Therefore approximately 50 pounds is required in the fully tilted position to establish a condition of equilibrium with the action of the spring, and 15 as this force is represented by the approximate unbalanced weight of the average person's body as it is tilted rearwardly practically no effort is required to maintain the back in tilted position.

The 25 pounds of spring support in the non-20 tilted position will provide adequate support for the back in the normal upright working posture, due to the fact that the chair back will not respond in this non-tilted position to the ordinary movements of the person in the chair. It will respond 25 however, to the voluntary effort of the person to tilt the chair back rearwardly, and thereupon, as the rearward tilting is increased, the unbalanced weight gradually equals the spring pressure and no appreciable effort will be required 30 to maintain the desired position of tilt.

It may be stated that this is almost the opposite effect from that obtained in ordinary posture chairs, where the line of action of the spring is tangent at the approximate center of the tilting range to the curve through which the spring connection with the tilting member moves. In this case there is practically no decrease in the rate of increase of tension applied to the spring, the distance of the spring compression is approximately the same as the angle of tilt, and there is no appreciable decrease in the torque arm as the tilting member is tilted rearwardly. This is clearly shown by the comparative diagram Fig. 8.

It will be assumed that the radius of the curve 45 C represented by the line A—B is 2 inches, that the length of the line V is 15 inches and the pressure W at the back in the non-tilted position is 25 pounds, these figures being the same as in the diagram Fig. 7. The torque lines T and T^3 are each approximately 2 inches and the distance of compression of the spring represented by the longitudinal movement of the line of action of the spring from P to P^3 is $\frac{1}{2}$ inch, this distance being equal to the angular 50 distance B— B^3 along the curve C. If the spring has an increase in resistance of 1000 pounds to one inch of compression, as in the diagram Fig. 7, then the increase of resistance for $\frac{1}{2}$ inch of compression will be 500 pounds. The formula 55 $W \times V = P \times T$ when reduced to figures will be

$$60 W(25) \times V(15) = 375 = P(187\frac{1}{2}) \times T(2)$$

This means that to provide 25 pounds support in the upright or non-tilted position the spring will 65 be adjusted to have an initial pressure of $187\frac{1}{2}$ pounds. When compressed $\frac{1}{2}$ inch the increase in spring pressure of 500 pounds will make a total pressure of $687\frac{1}{2}$ pounds. Thus in the fully tilted position the formula $W^1 \times V^1 = P^3 \times T^3$ when 70 reduced to figures will be

$$75 W^1(91\frac{3}{4}) \times V^1(15) = 1375 = P^3(687\frac{1}{2}) \times T^3(2)$$

Therefore approximately 92 pounds pressure is required in the fully tilted position to maintain 75 the back in this position, which is considerably

more than the unbalanced weight of the person seated in the chair.

Thus in the example, according to the invention, Fig. 7, the difference between 25 and 50 pounds representing the increase in pressure required between the non-tilted position and the fully tilted position is only 100 per cent, while in the example shown in Fig. 8 the difference, represented by the increase from 25 to 91 pounds, is approximately 268 per cent. Consequently, in 10 these previous structures it has been necessary in order to permit the chair back to be tilted rearwardly with a reasonable amount of ease to sacrifice any substantial support by the spring in the vertical position, so that the ordinary 15 movements of the person seated in the normal upright working position in the chair would cause the chair back to respond by moving rearwardly and the beneficial support that should be afforded by the chair back was lost.

20 A yoke shaped angle adjustment member comprising side portions 41—41 and a connecting portion 41^a is pivotally mounted between the rearward end portions of the sides of the tilting bracket member 17 by means of a cross pin 42 which extends through apertures 43—43 in the sides and through apertured ears 44—44 formed upon the upper ends of the side portions 41—41.

25 The connecting portion 41^a is provided in its lower edge with a rectangular cut-out 45 in which 30 is engaged a block 46 having pockets 47 in its ends in which the vertical edges of the cut-out 45 are engaged, the edges of the pockets 47 being divergent from the center line of the block whereby the portion 41^a may have limited tilt- 35 ing movement with respect to the block. A threaded hole 48 is provided through the block which is engaged by a screw shaft 49 journaled in a cylindrical passage 50 provided in the flange portion 27 of the tilting member, said shaft being 40 provided at its inner end beneath the lateral base portion 26 with a U-shaped bracket 51. A nut 52 is engaged upon the threaded shaft 49 adjacent the outer side of the flange 27 to retain the shaft against relative longitudinal movement. It 45 will be seen that upon rotation of the shaft 49 in one or the other directions the block member 46 is moved either toward or away from the flange 27 and in turn imparts swinging movement to the angle adjustment member about the pin 42. 50

The sides of the bracket 51 (see Fig. 10) are provided with holes 53—53, which are engaged by lugs 54 provided upon the vertical sides of a rectangular plate 55, provided upon its horizontal sides with lugs 56—56, which engage holes 57—57 55 of a U-shape bracket member 58 secured upon the end of a shaft 59, journaled in a U-shaped bracket 60 secured upon the base portion 26 by means of a bolt 61 and a nut 62. The axis of the shaft 59 is at an angle of 45° to the axis 60 of the shaft 49, although it may be at any desired angle, and through the universal joint connection between the shaft 59 and the shaft 49, provided by means of brackets 58 and 51 and the plate 55, rotation of the shaft 59 imparts 65 rotation to the shaft 49. This arrangement permits the shaft 59 to extend at one side of and forwardly of the bearing post 12, so that the handle 63 upon the end of the shaft may be located at a convenient point where it may be 70 readily reached by the occupant of the chair for the purpose of adjusting the angle of the back. By placing this handle forwardly, the occupant of the chair, in making the adjustment, will naturally lean forwardly, and therefore rearward 75

pressure upon the back will be relieved and the angular adjustment may be made with great ease. In chairs heretofore in use, where the means for angularly adjusting the back was arranged rearwardly of the chair structure, it was customary to lean backwardly in making the adjustment and pressure would therefore be exerted upon the back.

The sides 41-41 of the angle adjustment member are provided at their rearward marginal portions with V-shape bends 64-64, which are engaged by the forwardly and inwardly bent flanges 65-65 provided upon a height adjustment member 66. A strap member 67 is riveted 10 to the member 66 and extends at each side thereof where it is provided upon its ends with the vertical posts 68-68 upon the upper ends of which there is supported the back member 69, a portion of which is shown in Fig. 3. In one of 15 the side portions 41 there is provided a threaded bearing hole 70, the axis of which is at an inclined angle to the plane of said portion 41, the metal about the bearing being embossed, as at 20 71, to bring said axis into this relation.

25 A threaded shaft 72 is engaged in the bearing hole 70, and at its inner end is provided with a tapered wedge portion 73, which engages in the acute angle corner formed by the outer flange of the V-shape portion 64, at the opposed side of the 30 angle adjustment member from the bearing portion 70, and the inner surface of the height adjustment member 66. A handle 74 is provided upon the end of the shaft 72 which is disposed in a convenient location where it may be 35 conveniently turned by the person occupying the chair. The wedge portion 73 has bearing in an apertured bracket member 75 secured to the side portion 41. The height adjustment member is provided near its upper and lower ends with stop 40 lugs 76 and 77 in the path of the wedge portion 73, and which limit the extent to which the height adjustment member may be adjusted and at the same time prevent its accidental removal. The bracket 75 supports the inner end of the 45 shaft 72 against any tendency to bend, in the event that the height adjustment member is allowed to drop, bringing the stop lug 76 forcibly against the inner end of the shaft, and such as might occur when the shaft 72 is turned outwardly to loosen the connection of the height 50 adjustment member with the angle adjustment member.

The angle adjustment member is preferably formed of sheet metal, so that the sides thereof 55 are slightly springy, and, when the shaft 72 is turned outwardly to withdraw the tapered wedge end 73 from wedging engagement between the angle adjustment member and the height adjustment member, the sides 41-41 contract 60 slightly with respect to the flanges 65-65 so that they are relatively loose with respect to the latter. The strap member 67 may thereupon be grasped at each side and easily raised or lowered as desired to adjust the height of the back. 65 Thereupon the adjustment is fixed by turning shaft 72 inwardly causing the tapered wedge portion 73 to tightly wedge between the flange of the V-shape portion 64 at one side and the inner surface of the height adjustment member 70 66. At the same time the flange of the V-shape portion 64 at the other side is tightly pressed against the flange 65 of the height adjustment member through the outward spreading pressure exerted upon the side portion 41 as the tapered 75 wedge portion 73 is forced into place. The re-

sult of this is that in the adjusted position there is a tight engagement established between the flanges of the angular adjustment member and the flanges of the height adjustment member along the entire surfaces of the flanges of the angular adjustment member, and therefore an absolutely rigid relation is established, and this with very little effort required in the turning of the shaft 72 to establish this relation. In order to remove the back, for shipping purposes, it is only necessary to withdraw the shaft 72 to a point where the tapered wedge end 73 is out of the path of the stops 76-76, whereupon the height adjustment member 66 may be slipped off the angle adjustment member. 15

In Figs. 4 and 5, I have illustrated a modified form of the invention, in which the tilting member is formed of sheet metal and is mounted for tilting movement upon the bearing post 12, instead of upon the sides of the spider arms, as 20 in the first embodiment. The sheet metal tilting bracket member comprises an upper transverse portion 80 and side portions 81-81 bent downwardly at right angles thereto, the side portions being provided at their rearward upper 25 corners with apertured portions 82-82 in which the pivot pin 42 pivotally mounting the angle adjustment member is engaged.

The tilting member is mounted for tilting movement at the forward lower corners of the side 30 portions by means of a bolt 83 engaged through apertured bearing lugs 84-84 formed upon the bearing post 12, the sides 81-81 being disposed between these bearing lugs 84-84 and the side portions 13-13 of the bearing post, which 35 are secured to the angle iron spider arms 11-11 by means of rivets 14. The sides 81-81 of the tilting member are provided with lanced and outwardly embossed stop portions 85 and 86 between which are disposed the inner head ends of 40 the rearwardly disposed rivets 14-14, and which head ends act as limit stops for determining the degree of tilting movement of the tilting member, the stop portions 86 being engaged with the rivet heads in the non-tilted position and the stop 45 portions 85-85 engaging the rivet heads in the fully tilted position.

In the transverse top portion 80 there is provided toward its forward edge a cross-shaped opening 87, having lugs 88 bent upwardly from 50 its transverse portion and disposed at each side of its longitudinal portion, the rearward surfaces of these lugs forming with the upper surface of the top portion 80 V-shaped pockets in which are engaged the knife edge portions 89-89 of 55 the head 90 provided upon the end of the spring bolt 33, which bolt extends through the longitudinal portion of the opening 87.

A sheet metal plate 91 is disposed within the lower portion of the tilting member between the 60 sides 81-81, and is secured to said sides by means of lugs 92 formed upon its side edges and engaged and staked into apertures 93 formed in the sides 81-81, this plate being provided at its rearward end with a downwardly bent apertured flange 94 in which is supported the angle 65 adjusting screw shaft 49. The shaft 59 for operating the screw shaft 49 is mounted at the under side of the plate 91 in a similar manner to the mounting of the operating shaft 59 upon the under side of the base portion 26 in the first embodiment. Inasmuch as the angle adjusting and height adjusting parts are substantially identical to those of the first embodiment a further 70 description of these is not deemed necessary. 75

I have illustrated and described preferred and satisfactory embodiments of the invention, but it will be understood that changes may be made therein, within the spirit and scope thereof, as defined in the appended claims.

Having thus described my invention what I claim and desire to secure by Letters Patent is:—

1. In a back support for use in a chair, a chair back supporting member having a pair of spaced side portions, a vertically adjustable chair back member having a pair of spaced flanges engaged for vertical sliding movement with the outer sides of said side portions, and a screw shaft mounted in one of said members having a wedge end adapted to engage between one of said side portions and said back member to press said side portion tightly against one of said flanges.

2. In a back support for use in a chair, a chair back supporting member having a pair of spaced side portions, a vertically adjustable chair back member having a pair of spaced flanges engaged for vertical sliding movement with the outer sides of said side portions, and a screw shaft having threaded engagement in one of said side portions and having a wedge end adapted to engage between the other side portion and said back member to press said other side portion tightly against the adjacent flange, the other side portion adapted through said threaded engagement of said screw shaft therewith to be tightly pressed against said other flange.

3. In a back support for use in a chair, a substantially U-shaped chair back supporting member having a transverse portion and a pair of spaced rearwardly extending side portions, a vertically adjustable chair back member rearwardly of said supporting member having a pair of spaced flanges engaged for vertical sliding movement with the outer sides of said side portions, a screw shaft having threaded engagement in one of said side portions and having a wedge end adapted to engage between the other side portion and said back member to press said side portion tightly against one of said flanges, the other side portion adapted through said threaded engagement of said screw shaft therewith to be tightly pressed against said other flange.

4. In a back support for use in a chair, a chair back supporting member having a pair of spaced side portions, a vertically adjustable chair back member having a pair of spaced flanges engaged for vertical sliding movement with the outer sides of said side portions, one of said side portions having an inclined inner surface adjacent the inner surface of said back member, a screw shaft having threaded engagement in the other of said side portions and having a wedge end adapted to engage between said inclined inner surface and the inner surface of said back member to press said first side portion tightly against one of said flanges, the other side portion adapted through said threaded engagement of said screw shaft therewith to be tightly pressed against said other flange.

5. In a back support for use in a chair, a chair back supporting member having a pair of spaced side portions having outwardly diverging flanges at their rearward edges, a chair back member having a pair of spaced inwardly converging flanges engaged with the outer sides of said diverging flanges of said side portions, a screw shaft having threaded engagement in one of said side portions and having a wedge end adapted to engage between the diverging flange of the

other side portion and said back member to press said flange tightly against the adjacent flange of said back portion, the flange of the other side portion adapted through said threaded engagement of said screw shaft therewith to be tightly pressed against said other flange of said back portion.

6. In a back support for use in a chair, a chair back supporting member, a chair back member engaged with said supporting member for vertical sliding movement, a screw shaft mounted in one of said members having a locking end arranged to engage between said members to secure the back member in adjusted position, a pair of vertically spaced stop means on another of said members normally in the path of the locking end of said screw shaft to limit the relative vertical movement of said back member, said back member adapted to be removed from said supporting member upon retraction of said screw shaft to remove said locking end out of the path of said stop means.

7. In a chair, a post having spaced side portions, spider arms at the outer sides of said spaced side portions, headed rivets engaged through and securing said side portions and spider arms together, the rivet heads projecting inwardly from the inner surfaces of said side portions to form stop abutments, bearing means on said post, a tilting chair back supporting member mounted on said bearing means for tilting movement about a horizontal axis and comprising side portions inwardly spaced from said side portions of said post in opposed relation to said rivet heads, a pair of outwardly projecting stop portions on each of said side portions of said tilting member respectively disposed forwardly and rearwardly in the path of said rivet heads and adapted to engage said rivet heads respectively in the tilted and non-tilted positions of said tilting member, and spring means acting between said post and said tilting member to normally maintain said tilting member in non-tilted position.

8. In a tilting chair back support for use in a chair having a seat element, a bracket member mounted upon said seat element, a chair back supporting angle adjusting member hingedly connected to said bracket member having a transverse portion having a vertically sided slot open at one end, a rotatable screw carried by said bracket member, a nut engaged upon said screw, slot means in the sides of said nut pivotally engaging the vertical sides of said slot of said angle adjusting member whereby rotation of said screw imparts swinging movement to said angle adjusting member relatively to said bracket member, and means for rotating said screw.

9. In a tilting chair back support for use in a chair having a seat element, a bracket member mounted upon said seat element, a chair back supporting angle adjusting member hingedly connected to said bracket member having a transverse portion having a vertically sided slot open at one end, a block member having slot means in its sides pivotally engaging the vertical sides of said slot of said angle adjusting member, means connected to said bracket member engaging said block member and operative to adjustably move said block member whereby swinging movement is imparted to said angle adjusting member relatively to said bracket member.
